UNITED STATES PATENT OFFICE.

CARL P. BROCKWAY, OF TOLEDO, OHIO, ASSIGNOR TO INDUSTRIAL RESEARCH CORPORATION, OF TOLEDO, OHIO, A CORPORATION OF DELAWARE.

INTERNAL-COMBUSTION ENGINE.

Application filed October 22, 1920. Serial No. 418,803.

To all whom it may concern:

Be it known that I, CARL P. BROCKWAY, a citizen of the United States, residing at Toledo, in the county of Lucas and State 5 of Ohio, have invented certain new and useful Improvements in Internal-Combustion Engines, of which I declare the following to be a full, clear, and exact description.

10 This invention relates to the adjustment of the ports of a two cycle internal combustion engine of the sleeve valve type.

One object of the invention is to furnish 15 simple means for conveniently adjusting the area of the exhaust openings of a two cycle internal combustion engine under various loads.

Another object is to provide means for 20 adjusting the timing of the exhaust ports of the engine without effecting the timing of the intake ports.

A further object is to provide a cylinder 25 having sleeve valves and an adjustable compression chamber, the length of the cylinder being a minimum.

Another object is to vary the exhaust openings and compression chamber automatically with the amount of fuel charge.

Other objects and advantages relating to 30 details of construction and economies of manufacture will appear as I proceed with the description of that embodiment of the invention, which for the purpose of the present application I have illustrated in 35 the accompanying drawings:

Referring to the drawings:

Figure I is an elevation of the cylinder and head members embodying the principle of my invention.

40 Figure II is a vertical sectional view of the cylinder showing the adjustment of the cylinder head at full load with the throttle wide open.

Figure III is a sectional view similar to 45 Figure II but shows an adjustment of the cylinder head for light load with the engine throttled down.

Figure IV is a cross sectional view of 50 the cylinder taken along the line IV-IV in Figure II looking in the direction of the arrows.

Figure V is a cross sectional view of the cylinder taken along the line V-V in Figure III looking in the direction of the arrows.

In Figures I and II the cylinder wall is provided with exhaust ports 2, 2 and contains the piston 3, having a cylindrical sleeve 4, extending therefrom to perform the functions of a sleeve valve. The sleeve 60 4 is provided with exhaust ports 5, 5 to register with the ports 2, 2 in the wall of the cylinder, while at the piston end of the sleeve are the intake ports 6, 7 which register with the internal transfer port or 65 by-pass 8 in the cylinder wall. At the outer end of the cylinder is mounted the re-entrant cylinder head 9, secured to the outer surface of the cylinder wall by the screw threads 10 of large pitch, which permit the head to be rotated with respect to the cylinder wall thereby varying the position of the inner face of the cylinder head with respect to the exhaust ports 2, 2 and 70 sleeve ports 5, 5 while the relation of the intake ports 6, 7 to the port 8 remains unchanged. At diametrically opposite points upon the inner face of the cylinder head are cut away portions forming the recesses, or ports, 11, 11 which may be made to register with the exhaust ports 2, 5 as in Figure V, or may be rotated to a point between the exhaust ports, as in Figure IV, where they will have no effect upon the opening of 75 the ports 2, 5.

80 The threads 10 are of such a pitch that when the cylinder head 9 is rotated through an arc of less than 180 degrees the compression chamber is decreased in volume to such a degree that proper compression may still be obtained for small fuel charges. Any means may be used for rotating the cylinder head but I prefer to rotate it by means of a link mechanism between the throttle valve (not shown) and the operating rod 85 95 15 which is attached to the lug 16 which is integral with or rigidly mounted upon the cylinder head 9. When the throttle is wide open the head is screwed up to give a larger compression space and at the same 100 time the area of the exhaust passageway is lessened to prevent part of the large fuel charge to escape therethrough. In Figures II and IV, the cylinder head 9 is shown 105 adjusted to a position corresponding to full power output with the throttle wide open. It will be seen with this adjustment that the opening of the exhaust passageway by way of the clearance between the face of the cylinder head, and ports 5, 5 is limited, 110

when the piston sleeve valve approaches the limit of its downward travel. In the position shown the intake ports 6, 7 are open through the by-pass 8, whereby the inrushing supply of gas will scavenge the explosion chamber, and drive out the exhaust gases efficiently through the limited openings created by way of the ports 5, 5 as these ports are uncovered by the downward motion of the sleeve 4, and register with cylinder ports 2, 2.

In Figures III and V the cylinder head 9 is shown adjusted to a position corresponding to small power output where the engine is subjected to a light load. The position of the recesses 11, 11, is such that they register with exhaust ports 5, 5 as shown in Figure V. By reason of the position of these recesses, the sleeve 4, in traveling down, will uncover the ports 5, 5 at an earlier time than in the case of Figure II, and will thus afford a larger opening for a longer period of time than in the case of Figure II. With this adjustment of the cylinder head, and the more limited supply of inrushing gas occurring at light load, the products of combustion can be easily ejected through the exhaust openings, which are rendered large by the registering of the recesses 11, 11 with the ports 5, 5 and 2, 2.

It is obvious that the cylinder head may be made to assume positions intermediate of those shown in Figures II and III, whereby a portion only of the recesses 11, 11 will register with the ports 5, 2 thus providing for intermediate load conditions. The cylinder head may be turned manually, or by mechanism associated with the engine, to accommodate the engine to the various load conditions.

In engines of the sleeve valve type, the cylinder is generally of greater length than in other types of engines, and it is therefore desirable to reduce this length as much as possible. By threading the head 9 to the outer surface of the cylinder wall 1, the sleeve 4 may travel to the extreme end of the cylinder, thus utilizing the full length of the cylinder wall to the best advantage, and permitting the use of any desired length of the threaded portion upon the outside surface of the cylinder wall, without increasing the length of the cylinder.

I am aware that the particular embodiment of my invention above described, and illustrated in the accompanying drawing is susceptible of considerable variation without departing from the spirit thereof, and therefore I desire to claim my invention broadly, as well as specifically, as indicated by the appended claims.

I claim as my invention:

1. In an internal combustion engine, a cylinder, a piston therein, said cylinder having a head co-operating with said piston and

the walls of said cylinder for varying the time of exhaust independently of the time of intake.

2. In an internal combustion engine, a cylinder, a piston therein, said cylinder having a rotary head co-operating with said piston and the walls of said cylinder for varying the time of exhaust. 70

3. In an internal combustion engine, a cylinder, a piston therein, said cylinder having a head co-operating with said piston and the walls of said cylinder, and adjustable rotatably within said cylinder for varying the time of exhaust independently of the time of intake. 75

4. In an internal combustion engine, a cylinder member, a piston including a sleeve member, and a cylinder head member fitting within said sleeve member, ports in each of said members registering with each other at one portion of the stroke, and means to vary the time of registering of the ports in said sleeve and cylinder members. 80

5. In an internal combustion engine, a cylinder member, a piston including a sleeve member, and a cylinder head fitting within said sleeve member, ports in both of said members, the ports in said sleeve member being covered and uncovered by said head as said piston reciprocates, and means supporting said head for varying the time of covering and uncovering of said sleeve ports by said head. 85

6. In an internal combustion engine, a cylinder, a piston therein, said cylinder having an inwardly extending head co-operating with said piston and the walls of said cylinder for varying the time of exhaust. 90

7. In an internal combustion engine, a cylinder having ports in the walls, a piston having a sleeve extension thereon containing ports to register with said cylinder ports, said cylinder having a head fitting within said piston sleeve and provided with means to vary the time of opening of said piston sleeve ports, including a cut away section at a portion only of the innermost end of said head adjacent said sleeve. 95

8. In an internal combustion engine, a cylinder having ports in the walls, a piston having a sleeve extension thereon containing ports to register with said cylinder ports, said cylinder having a head fitting within said piston sleeve and provided with means to vary the time of opening of said piston sleeve ports including two recesses at diametrically opposite sides of the inner face of said head. 105

9. In an internal combustion engine, a cylinder, a piston including a sleeve valve, and a head revolvably supported on said cylinder, and co-operating with said sleeve valve for varying the area of the exhaust openings of the cylinder. 115

10. In an internal combustion engine, a 120

- cylinder, a piston including a sleeve valve, and a head supported on said cylinder and co-operating with said sleeve valve, said head being adjustable in an axial and an 5 angular direction for varying the compression space and the exhaust openings of the engine.
11. In an internal combustion engine, a cylinder, a piston including a sleeve valve, 10 and a head threaded upon said cylinder and co-operating with said sleeve valve for varying the size of the exhaust openings of the engine.
12. In an internal combustion engine, a cylinder, a piston including a sleeve valve, 15 and a head threaded upon the outer surface of said cylinder, and co-operating with said sleeve valve for varying the size of the exhaust openings of the engine.
- 20 13. In an internal combustion engine, a cylinder having exhaust opening, a throttle valve, and means for varying the compression space in said cylinder, and varying the exhaust openings simultaneously with the 25 varying of the throttle position.
14. In an internal combustion engine, a cylinder having exhaust opening, a throttle valve, and means for varying the compres-
- sion space in said cylinder, and varying the exhaust openings automatically by varying 30 of the throttle position.
15. In an internal combustion engine, a cylinder having a movable head, a throttle valve, common means for varying the compression space in said cylinder and the size 35 of the exhaust opening of said cylinder.
16. In an internal combustion engine, a cylinder having a movable head, a throttle valve, common means for varying the compression space in said cylinder and the size 40 of the exhaust opening of said cylinder simultaneously with the varying of the throttle position.
17. In an internal combustion engine, a cylinder having exhaust opening, a throttle 45 valve, and means for varying the exhaust opening simultaneously with the varying of the throttle position.
18. In an internal combustion engine, a cylinder having exhaust opening, a throttle 50 valve, and means for varying the exhaust opening automatically by the varying of the throttle position.

In testimony whereof, I affix my signature.

CARL P. BROCKWAY.
